UNITED STATES PATENT OFFICE.

JOHN P. ROGERS, OF TOPEKA, KANSAS.

REINFORCED CONCRETE MANHOLE-COVER.

No. 908,805.

Specification of Letters Patent.

Patented Jan. 5, 1909.

Application filed April 16, 1908. Serial No. 427,326.

To all whom it may concern:

Be it known that I, JOHN P. ROGERS, a citizen of the United States, residing in Topeka, in the county of Shawnee and State 5 of Kansas, have invented a new and useful Improvement in Reinforced Concrete Man-hole-Covers, of which the following is a specification.

My invention relates to the coverings for 10 man-holes for sewers, telephone and telegraph conduits, steam-pipe conduits, and all underground passages requiring man-holes, and as well openings for coal-holes, cellars, and the like.

15 The object of my invention is to do away with the usual heavy metal castings heretofore used for such purposes and weighing, usually, several hundred pounds, and to substitute therefor a skeleton metal frame-work 20 of economical construction and light weight and suitable as the reinforcement for concrete, of which the main body of the structure is to be built.

It consists primarily of a metal lattice-work collar, a metal base portion, and a metal rim; and it also consists of the parts, improvements, and combinations herein-after pointed out and claimed.

25 In the drawings accompanying and forming part of this specification, and in the description thereof, I have shown my invention in its preferred form, and have shown the best mode of applying the principles thereof; but it is to be understood that 30 my invention is not confined to the exact details shown in the drawings and in the description of the drawings, and that I contemplate changes in form, proportions, and materials, the substitution of equivalent 35 members and the transposition of parts, within the scope of the appended claims, 40 without departing from the spirit of the invention.

Figure 1 is a plan view of a man-hole 45 cover made in accordance with the principles of my invention and comprising both the frame-work for the man-hole opening and the removable cover proper, the right half of the view showing the concrete applied to the frame-work, and the left half showing the skeleton metal frame. Fig. 2 50 is a sectional view of the structure shown in Fig. 1 taken on a plane approximately through the center, the removable cover 55 being elevated. Figs. 3, 4, 5, and 6, are

enlarged sectional views of the rim for the base portion, a modified form of said rim, the rim for the collar portion, and the rim for the removable cover, respectively.

Similar reference characters indicate like 60 or corresponding parts throughout the several views.

For the neck or collar of the man-hole opening, I use an open or lattice-work metal collar 7, preferably expanded metal, and for 65 the base portion I use a metal portion, preferably also expanded metal, 8; parts 7 and 8 may be either integral with each other or separate. Mounted on the collar 7 is a metal rim 9 having an annular channel 10 in 70 its under side for receiving the upper edge of the collar 7. Concrete, 11, is to be filled in on both sides of the collar and base portions 7 and 8, the shape being made by means of templets. To protect the outer 75 edge of the base portion, the angle iron 12 may be used; or a channel-iron 13 may be used to protect also the upper edge.

The rim 9 has a step or ledge 14 to receive the removable cover 15. The cover may be 80 made with an outer protecting rim or shield 16, which may be stepped to correspond to the rim 9. On one of the steps or ledges may be laid the Johnson bar rods, or other suitable reinforcement, 17, and the cover 85 may then be filled with concrete 19, as indicated. For ventilating holes, I prefer to use a number of short pipes, each with its lower portion smaller than its upper portion so as to form a shoulder which may rest on 90 the Johnson bar rods and thus be held firmly in place, these pipes being indicated by the numeral 18.

It has been the practice heretofore to construct the man-hole opening of cast metal, 95 which weighs several hundred pounds for each one. They are therefore very heavy for handling, while in the matter of shipping, the cost of transportation is a considerable item. With my invention, however, I contemplate that the skeleton frame-work only need be thus handled and shipped, thus effecting a considerable saving in metal and in transportation charges; and also I provide a metal frame which is easily 100 handled on account of its light weight and convenient form.

To construct the cover when the frame-work is provided, I prefer to spread a paper over the top of the walls of the man-hole, 110

then set the rim 12 in place thereon, then fill in the required depth of concrete, then set the base portion 8 and the collar 7 and the rim 9 in place, then, using a templet or templets, fill in the remaining concrete; this work being done at the man-hole, and usually with materials already there.

What I claim is:

1. A metal frame-work for a reinforced concrete manhole cover, comprising a metal lattice-work collar portion, a metal base portion, and a separate metal rim, substantially as set forth.
2. A metal frame-work for a reinforced concrete manhole cover, comprising a metal lattice-work collar portion, a metal lattice-work base portion, and a separate metal superposed rim for supporting a removable cover.
3. A metal frame-work for a reinforced concrete manhole cover, comprising an expanded-metal collar portion, an expanded-metal base portion, and a separate metal superposed rim for supporting a removable cover, said rim having an annular channel in its under side to receive the collar portion.
4. A metal frame-work for a reinforced concrete manhole cover, comprising a metal lattice-work collar portion, a metal lattice-work base portion, and a separate metal superposed rim having a channel in its underside to receive the collar portion.
5. A metal frame-work for a reinforced concrete manhole cover, comprising expanded-metal collar and base portions, a protecting rim around the outer edge of the base portion, and a separate superposed rim for supporting a removable cover and having a channel in its underside to receive the collar portion.
6. The combination of expanded - metal collar and base portions, a metal superposed rim, concrete forming the main body of the

collar and base on both sides of the expanded metal, and a removable cover supported on said rim. 45

7. The combination of expanded - metal collar and base portions, a superposed metal rim, concrete forming the main body of the collar and base on both sides of the expanded metal, a metal protecting rim around the outer edge of the base, a removable cover supported on the superposed rim and comprising an outer metal protecting rim, a metal reinforcement, and concrete on 50 both sides of the reinforcement and forming the main body of the said removable cover.

8. A removable cover for man-holes, comprising a metal outer protecting rim, a series of Johnson bar rods supported thereon, a 60 series of pipes extending through said cover and having shoulders to hold them in place, and concrete forming the main body of the cover.

9. The combination of expanded metal collar and base portions, a superposed metal rim, concrete forming the main body of the collar and base on both sides of the expanded metal, and a removable cover supported on the rim and comprising an outer 70 metal protecting rim, a metal reinforcement, and concrete on both sides of the reinforcement and forming the main body of the cover. 65

10. In a manhole collar and cover, the 75 combination of a metal base portion, a metal lattice-work collar portion, concrete forming the main body of the collar and base on both sides of said metal portions, and a metal superposed rim. 80

In testimony whereof I have hereunto signed my name in the presence of witnesses.

JOHN P. ROGERS.
